Specification for Design.

Patented May 31, 1910.

Application filed March 30, 1910. Serial No. 552,477. Term of patent 8½ years.

To all whom it may concern:

Be it known that I, ADOLPH PETZOLD, a citizen of the United States, residing in the city of Philadelphia, State of Pennsylvania, have invented a certain new, original, and ornamental Design for Rugs, of which the following is a specification, reference being had to the accompanying drawing, which is a plan view of a quarter-section thereof on a carpet-rug, each of the other three quarter-sections being identical therewith.

I claim:—

The ornamental design for a rug, as shown.
